UNITED STATES PATENT OFFICE.

PERCIVAL G. BURGESS, OF JAMAICA, NEW YORK, ASSIGNOR, BY MESNE ASSIGNMENTS,
TO GENERAL ACOUSTIC COMPANY, A CORPORATION OF NEW YORK.

INTERCOMMUNICATING TELEPHONE SYSTEM.

1,080,260.

Specification of Letters Patent.

Patented Dec. 2, 1913.

Application filed September 29, 1910, Serial No. 584,414. Renewed February 12, 1913. Serial No. 748,017.

To all whom it may concern:

Be it known that I, PERCIVAL G. BURGESS, a citizen of the United States, residing at Jamaica, in the county of Queens and State 5 of New York, have invented a new and useful Intercommunicating Telephone System, of which the following is a specification.

This invention relates to intercommunicating telephone systems and more particularly to systems including a plurality of stations each having two special or local instrument line wires which are common to all the other stations and which at any station are adapted to be connected by suitable jacks 5 or keys to the instruments thereat; thereby putting said last mentioned station into communication with this first. By "instrument" I mean a telephone set including transmitter receiver and current source.

6 The present invention consists in a variety of correlated purposes, and in the means and combinations for effecting the same as hereinafter more particularly pointed out and claimed.

5 Among the various aspects of the invention, the following may be mentioned for the purposes of a general statement as to its nature and objects.

One purpose or aspect is that no station 0 can be left in such a way as to interfere with the use of the system; in other words, the leaving of a plug in any jack or plugs, even in two stations simultaneously on the same or different lines, will neither produce a ringing of any buzzer or interfere with the talking of any parties in the system. This result is partly due to the feature of the construction that provides a bus-bar common to all the jacks and which is normally 5 in the talking battery circuit at each station, but which is wholly disconnected and put into the ringing battery circuit at the time of making a call. The result is also due to the nature of the connections established by the switch hook at each station. This result further has a particular utility in its combination with the non-conducting plug which I prefer to employ on account of its simplicity, and which accomplishes in its combination with the circuit of this invention the same purposes as have been previously effected by systems with automatically releasable devices.

A further object of the invention lies in

the means by which a call may be made from 55 any station whether the receiver thereat is on or off the hook.

A further feature of invention lies in securing non-interference between the circuits under all talking and ringing conditions, and the accomplishing of this as well as the first mentioned purposes, with a limited number of contact points at the jacks.

A further feature of the invention lies in providing a common battery for the talking 65 circuits and a common battery for the ringing circuits, but in so arranging the circuits that under no normal conditions will both poles of one battery be put in any circuit relation which includes more than one pole 70 of the other battery, nor under any condition will the battery circuits interfere with one another.

A further feature of the invention lies in the provision of a means whereby any 75 station of the intercommunicating system may be put in connection with a three wire dictograph system (later identified) and secure the requisites of a dictograph installation.

A further feature of invention lies in the 80 arrangement of the circuits whereby the talking battery never gets into the ringing circuit or the ringing battery into the talking circuit; nor the ringing battery into the ringing circuit except when intended. This 85 is important in that it avoids "pops" in the receivers and false rings in the buzzer or bell.

The invention of the present application 90 may be embodied in considerably varying forms so far as the mechanical features are concerned, the claims of this case being more particularly directed to electrical circuits.

In addition to this the mounting of the transmitter presents certain features of novelty 95 in its detachable support, and in its separation from the inclosing case.

In the drawings, Figure 1, is a front view of a telephone set for one of the stations of an intercommunicating system embodying the principles of my invention; Fig. 2, is a view of the same with the cover and transmitter removed; Fig. 3, is a vertical sectional view of the same; Fig. 4, is a detail horizontal sectional view of the jacks on the 100 line 4, 4, of Fig. 3; Fig. 5, is a vertical sectional view on the line 5, 5, of Fig. 3; Fig. 6, is a side elevation of the transmitter; Fig. 7,

is a top view of the transmitter; Fig. 8, is a bottom view of the transmitter; Fig. 9, is a diagrammatic view showing the arrangement of the circuits; Fig. 10, shows the circuits for the connection of a dictograph in the system as above referred to; Fig. 11, is a diagrammatic representation of the circuits when a dictograph is used.

Referring to the drawings, 1 denotes a suitable housing preferably composed of a base 2 and sheet metal cover 3 having an opening or openings 4 for the entrance of sound to the transmitter, and openings 5 through which a plug is received as later described. Mounted on a base 2 within the cover 3 is a jack-frame 6, particularly shown in Fig. 5. I prefer to make the jack-frame of channel or H shape transverse section and of either sheet or cast metal. This construction provides base-lugs 7 and transverse lugs or face plate 8 at the top. The face plate 8 may be in one or two parts.

9 denotes what I shall term the bus-bar support, and which in effect comprises two bus-bars with intervening insulation adapted to support the various springs 11, 11¹ of the jacks and ringing key. Each group of springs 11 constitutes a complete jack or unit, and as many as desired may be provided. In the drawings I have shown eleven in all; five on one side and six on the other. All the jacks 11 are alike. The ringing key 11¹ I will specially refer to. The bus-bars proper are denoted 13 and 14, of which 14 is substantially heavy and constitutes a frame into which the screws 16 which clamp the other bus-bar and insulation are received. The various springs 11 are grouped in sets of four corresponding to the individual jacks, and the two outside springs bear directly against the adjacent bus-bars 13 and 14 against which such springs are clamped. The intermediate pair of spring blades of each jack have downward extensions to which circuit wires are attached, as later described. The ringing key 11¹ is of slightly different construction, in that one of the outside spring blades does not bear against the corresponding bus-bar 14, but is insulated therefrom. This ringing key 11¹ also differs from the other jacks in that the second and fourth spring blades project upward to be engaged by the wedge 17, whereas in the jacks 11 it is the two middle spring blades which project upward for engagement by a suitable plug. The plug employed is denoted 18 and may have any suitable handle. This plug is of insulating material and has no wire connection in any circuit or with any part of this structure. It is evident that the screws 16 may be received between the springs 11 as shown, or may be bushed through the springs if desired. As shown the spring blades are rigidly fixed in their proper positions by

the recesses in the insulation in which said springs are embedded, and also by the clamping engagement of the bus-bars 13 and 14. The same result may be obtained by the use of two screws with insulating bushings 70 for each blade. The plug 18 is guided into proper position with the spring blade by the holes 19 in the face plate 8 of the frame 5.

It will be observed by the foregoing construction that a rigid guide is provided for the plug and a rigid support for the spring blades, all of simple and compact construction and adapted to complete the electrical circuits in a very simple way.

On another part of the base 2 is provided a pair of upright spring prongs 20 and 21 each of which has a laterally extended forked-ear at its upper end.

23 denotes a transmitter. I prefer to employ a very sensitive transmitter, such as is employed with the "dictograph" U. S. Patent No. 843,186. 25 and 26 denote the circuit terminals of this instrument composed of studs adapted to be received in the 90 forked-ears 22. This arrangement holds the transmitter in proper relation to the openings 4 of the cover and also out of contact with the cover which is advantageous in that it lessens the effect of vibration due 95 to extraneous causes.

30 denotes a receiver switch hook on which a receiver, such as shown for example on Patent 843,186, may be hung, and 32 denotes spring blades controlled by the 100 switch hook 30.

33 is a buzzer of ordinary construction and 34 are a pair of retardation coils in circuits as hereinafter described.

A diagram of the electric circuits is shown 105 particularly in Fig. 9. In this figure the system is shown in its normal condition, that is with all the plugs removed and all the ringing and talking circuits open. The receiver at each station is here shown at R, the transmitter at 23, the bell, buzzer or indicator at 33, the retardation coils at 34, the switch hook at 30, the ringing key at 17, and a pair of bus-bars 13 and 14 with connections for an intercommunicating system of 110 four stations. The spring blades collectively 115 designated 11 in Figs. 4 and 5, are here diagrammatically illustrated in an obvious manner in their connection with the bus-bars and in their relations to receive the 120 plug 18. The various spring-blades will be later particularly referred to.

It is characteristic of my system that two electric conductors which for the purpose of a convenient designation may be termed 125 bus-bars at each station form part of the series of jacks thereof and that one of these bus-bars, denoted 14, is connected to the local telephone set or instruments, and also to one of the two line wires which cor- 130

respond or pertain particularly to that individual station, which may be termed local instrument wires for such particular station. I prefer to make these connections permanent. The other bus-bar 13 has no permanent connection with anything, but has a single wire connection m^1 with a contact 41 which is normally closed, but which is opened when the signaling key 17 is depressed. 5 When this contact is closed, however, the circuit is made from said bus-bar 13 to the local telephone set or instrument R, 23 through wire m^2 . When the ringing key is depressed so as to break this circuit at 41 10 another connection is established at 51 from the bus-bar 13 to a source of current o through wire m^3 , thereby making the bus-bar 13 temporarily what might be termed a potential bus-bar. Both bus-bars 13 and 15 14 have contacts by which, through the spring-blades, jacks or keys A, B, C, D, etc., they can be connected to any one of a plurality of pairs of the local instrument wires of other stations. It is further characteristic 20 of the present invention that the bell or indicator 33 has a permanent connection with the other terminal G of the source of current mentioned, which may be termed for convenience, the ringing battery. 25

30 The telephone set at each station comprising the usual transmitter and receiver, in addition to the connections already referred to, is bridged across a source of current t , t^1 through retardation coils 34, thus supplying 35 the necessary electric energy for the purpose of producing the current voice pulsations in accordance with ordinary practice. The switch hook normally establishes a contact 42 for the bell or buzzer 33, and 40 from which current may be derived through a wire n^1 from one of the local instrument wires as shown for example at a^2 . The circuit of the telephone set is normally open at the point 50, but is closed at this point 45 45 and a circuit further established to the said local instrument wire a^2 when the switch hook rises.

For the purposes of the electric features of the present invention the elements which 50 have been termed bus-bars may of course be any suitable or equivalent conductors, and I do not desire to be limited or restricted to the particular mechanical construction as shown.

55 By the foregoing all the purposes mentioned in the preliminary part of this specification are accomplished. This may be readily analyzed and found to be the case, it being understood that the polarity of the 60 respective batteries or current sources is made as indicated in the drawings (or the reverse in both batteries which is obviously an exact equivalent). For the purposes of this specification it will not be necessary to 65 do more than trace the circuit conditions in

which may be termed the usual or normal operation, *i. e.* when one party calls another and talks to him, the various plugs being out of their jacks except that plug inserted at the calling station for the purposes of the 70 particular call and conversation under consideration.

I will assume that station P^A desires to call station P^C . Party P^A places the plug in jack C and depresses the ringing key 17. 75 The ringing circuit is as follows, potential wire o , wire m^3 (station P^A), blade 51, wire m^1 , bus-bar 13, righthand-blade of jack C, wire C^2 , line wire c^2 , wire n^1 of station P^C , hook 30, bell 33, wire n^2 back to G which is 80 the other terminal of the ringing battery. Station P^C being called in this way, removes receiver from hook, and station P^A (who may have removed receiver before or after calling) talks and listens through a circuit 85 as follows, transmitter 23, receiver R, wire l^2 , bus-bar 14, lefthand-blade of jack C, wire C^1 , line wire c^1 , wire l^1 of station P^C , receiver R, transmitter 23, switch hook 30, wire n^1 , line wire c^2 back to station P^A , wire C^2 , 90 righthand-blade of jack C, bus-bar 13, wire m^1 , wire m^2 back to transmitter 23. It will be observed that this circuit is equally adapted for talking and listening in both 95 directions. Inasmuch as all the stations of the system are identical, the operations of any other call or conversation are exactly like those already described.

I provide means by which the present intercommunicating system may be used in 100 connection with the dictograph, such for example as is disclosed in Patent No. 927,230. As described in the patent mentioned, a dictograph station has a plurality of three 105 wire circuits extending therefrom to the various stations to which communication is desired and such a three wire circuit is illustrated in Fig. 10 and comprises wires p , q , and r . The circuits of the dictograph proper do not form any part of the present invention except in their combination with the circuits of the present intercommunicating system, and for this purpose a 110 diagram of Fig. 11 may be referred to which illustrates the circuits after the dictograph 115 station and intercommunicating station P^A have been put in communication. r may be referred to as a dictograph transmitter wire, p a dictograph common battery wire, and q a dictograph receiver or loud speaker wire. 120 The wires q and r may be simply connected to the wires a^2 and a^1 of station P^A , and the wire p connected into the wire k between the transmitter 23 and receiver R. This provides for circuits as shown in Fig. 11, 125 and further provides for calling party P^A from the dictograph station, and the dictograph station from party P^A . The circuit when party P^A is talking is as follows, transmitter 23, switch hook 30, wire q , spring 130

blade 80, contact 81, wire 82, receiver or loud speaker X of dictograph station, wire 83, battery B³ of dictograph station, wire 84, wire 85, blade 86, contact 87, wire p back to transmitter 23. The circuit when the party at the dictograph station is talking is as follows, transmitter Y of dictograph station, wire 90, contact 91, spring blade 92, wire r, wire l¹, receiver R, wire p, spring blade 87, contact 86, wire 84, dictograph battery B³ back to transmitter Y. In calling the dictograph station from party P^A, the circuit is as follows, negative battery B⁴, wire m², contact 51, wire m¹, spring blade 94, wire n¹, wire q, wire 80, contact 95, contacts 96 and 97, wire 98, dictograph signal S back to positive battery B⁴. The circuit when the dictograph station calls party P^A, is as follows, spring blade 96, contact 99, wire 100, wire 85, battery B⁴, wire 102, wire n², buzzer 33, switch hook 30, wire q, blade 80, contact 95 back to spring blade 96. It is to be understood that the spring blades or key of the dictograph station is substantially that shown in the prior patents already referred to, the blades 80, 86 and 92 being depressed for talking purposes and the blades 96 being elevated for calling purposes. It does not however provide for secrecy of the conversation between the dictograph station and party P^A. In order to provide for secrecy I provide a jack A at station P^A constructed as shown in Fig. 10, and by which all connection to the wires a¹ and a² is interrupted when a plug is inserted in this jack during a dictograph conversation. It will be observed that the electric circuits are otherwise the same as if the wires r and q had been respectively joined to local instrument wires a² and a¹. Also it will be observed that under normal conditions when no plug is in the jack A, the circuits of station P^A to the other stations of the intercommunicating system are exactly as already described in connection with Fig. 9. During the dictograph conversation there is a separate talking circuit from each party to the other.

It is a characteristic of the system as above described that conversation directly into a transmitter is not required; on the contrary it is merely necessary to talk in an ordinary tone anywhere within the length of the receiver cord and the effects are as distinct and audible as in any ordinary telephone usage. This of course is due to the nature of the transmitter and its method of support rather than the circuits, but it makes the system a perfect combination of convenience and efficiency from a practical standpoint. When the system is used in connection with a dictograph it will be observed that the talking circuits are altered to suit the character of dictograph work.

65 What I claim is:—

1. In an intercommunicating telephone system, a station having two bus-bars, a telephone transmitter, a telephone receiver, and two local instrument wires, a dictograph station, a wire therefrom joined to a point in a circuit between said transmitter and said receiver, two other dictograph wires adapted to be included in circuit with said bus-bars, and means for interrupting the connection of said transmitter and receiver with said local instrument wires. 75

2. In an intercommunicating telephone system, a station having two bus-bars, a telephone transmitter, a telephone receiver, and two local instrument wires, a dictograph station, a wire therefrom joined to a point in a circuit between said transmitter and said receiver, two other dictograph wires adapted to be included in circuit with said bus-bars, means for establishing the dictograph connection, and means for interrupting the connection of said transmitter and receiver with said local instrument wires when such dictograph communication is established. 80

3. In an intercommunicating telephone system, a station having bus-bars and a telephone receiver and a telephone transmitter, a dictograph station, a wire from said dictograph station joined to a point in a circuit between said transmitter and said receiver, and two other wires from said dictograph station adapted to be included in circuit with said bus-bars. 95

4. In an intercommunicating telephone system, a plurality of stations each having telephone instruments and a pair of local instrument wires, a bus-bar at each station joined to one instrument wire and also to the instruments at its station, a switch hook normally disconnected from said instruments and joined to the other instrument wire, a potential source, two upper contacts for said hook one of which is connected to the circuit of said instruments, a second bus-bar normally connected to the other said contact, means for disconnecting said second bus-bar from said contact and putting it in connection with said potential source, a plurality of local instrument wires from other stations, and means for joining said bus-bars in circuit with the wires of any selected station. 105 110 115

5. In an intercommunicating telephone system, a plurality of stations each having telephone instruments and a pair of local instrument wires, a conductor at each station joined to one instrument wire and also to the instruments at such station, a switch hook normally disconnected from said instruments and joined to the other instrument wire, two upper contacts for said hook, one of which is connected to the circuit of said instruments, a second conductor normally in electric connection with said other 120 125 130

contact, a plurality of local instrument wires from other stations, and means for joining said conductors in circuit with the wires of any selected station.

- 5 6. In an intercommunicating telephone system, a plurality of stations each having telephone instruments and a pair of local instrument wires, a conductor at each station joined to one local instrument wire and also 10 to the instruments at such station, a switch normally disconnected from said instruments and joined to the other local instrument wire, two upper contacts for said hook one of which is connected to the circuit of said instruments, a second conductor normally connecting with said other contact, means for disconnecting said second conductor from said contact, and means for joining said conductors in circuit with the wires of any selected station.

- 15 7. In an intercommunicating telephone system, a plurality of stations each having telephone instruments and a pair of local instrument wires, a bus-bar at each station joined to one instrument wire and also to the instruments at such station, a switch normally disconnected from said instruments and joined to the other instrument wire, two upper contacts for said hook one of which is connected to the circuit of said instruments, a second bus-bar normally connected to said other contact, means for disconnecting said second bus-bar from said contact during the act of making a call, and means for putting 30 said bus-bars in circuit with the wires of any selected station.

- 35 8. In an intercommunicating telephone system, a plurality of stations each having telephone instruments and a pair of local

instrument wires, a bus-bar at each station 40 normally joined to one instrument wire and also to the instruments at such station, a switch normally disconnected from said instruments and joined to the other instrument wire, two upper contacts for said hook 45 one of which is connected to the circuit of said instruments, a second bus-bar normally connected to said other contact, a plurality of jacks for said bus-bar and a non-conducting plug at each station for said jacks adapted to put said bus-bars in circuit with the wires of any selected station.

9. In an intercommunicating telephone system, a plurality of stations each having telephone instruments and a pair of local 55 instrument wires, a talking battery, a conductor at each station joined to one instrument wire and also to the instruments at such station and to a pole of certain sign of said battery, a switch normally disconnected 60 from said instruments and joined to the other instrument wire, a second battery, a normally open switch contact, a second conductor normally electrically connected to said contact, means for disconnecting said second 65 conductor from said instruments and putting it in connection with the pole of opposite sign of said second battery, and means for joining said conductors in circuit with the wires of any selected station. 70

In testimony whereof, I have hereunto set my hand, in the presence of two subscribing witnesses.

PERCIVAL G. BURGESS.
